UNITED STATES PATENT OFFICE.

BRUNO ROSENBAUM, OF BERLIN, GERMANY, ASSIGNOR TO WESTINGHOUSE ELECTRIC & MANUFACTURING COMPANY, A CORPORATION OF PENNSYLVANIA.

CATHODE ENERGIZED BY ALTERNATING OR PULSATING CURRENTS.

Application filed September 2, 1921, Serial No. 498,183, and in Germany February 12, 1919.

This invention relates to a means for heating the cathode in a thermionic device.

It is an object of this invention to provide means through which the heat may be supplied by alternating current or by current containing an alternating component, without causing corresponding noise in the telephones of the signal system.

It is a further object of this invention to cause the filament of a thermionic device to be heated without direct application of the heating current thereto.

Other objects of the invention, together with structural details of the device, will be apparent from the following description and the accompanying drawing which consists of a single figure diagrammatically illustrating the structure.

The drawing shows a vacuum device 1 having a cathode 2 which is supported by a press 3. A grid 4 and an anode 5 are shown supported by another press 6 and located in close proximity to a portion of the cathode 2. The cathode is surrounded by a mass 7 of good heat-conducting material, preferably metal. This is supported in any desired manner, for example, by standards 8 entering the press 3. The mass 7 has a passage 9 through the 25 metallic mass 7 is insulated from the cathode and yet is in close proximity thereto. The mass 7 is surrounded by a coil 11 which is supplied through leads 12 that extend through the press. These leads are supplied with current from a source 13. A lead 15 for the grid 4 and a lead 16 for the anode 5 are shown extending through the opposite press 6.

In the operation of the device, current from the source 13 is delivered over the leads 12 to the coil 11 and heats this coil. It also heats the mass 7 partly by direct flow of heat from the coil 11 into this mass and partly by induction currents set up therein. The hot mass 7 heats the filament 2. The heat is

transferred from the mass 7 to the filament 2 principally by radiation. The vessel 1 being evacuated, very little transfer by convection takes place and the mass 7 being separated from the filament 2, practically no heat conduction occurs between them. The radiation is, however, enough to heat the filament strongly because a considerable length of the filament is in close proximity to the mass 7.

The hot filament 2 emits electrons which pass to the anode 5. The flow of these electrons is controlled by the grid 4. The external connections to the filament, grid and anode are varied according to the use to which the vacuum device is put. These connections are not illustrated and are not further described because the invention is equally applicable to all tubes however used.

It will be understood that many details of the construction may be varied through a wide range without departing from the principle of this invention. I, therefore, do not intend that the patent shall be limited except as necessitated by the prior art or indicated by the claims.

I claim as my invention:

1. In a thermionic device, a thermally conductive member at least one portion of which is adapted to emit electrons when hot, means including a body of large thermal capacity around said thermally conductive member, and a heating coil surrounding said body for heating at least one portion of said thermally conductive member, and means cooperating with that portion of the thermally conductive member which emits electrons to form a space-current device.

2. In a thermionic device, a cathode, a heating member in proximity to said cathode and a heating coil surrounding said member.

In testimony whereof I affix my signature.

BRUNO ROSENBAUM.
